Primary Examiner — T Chase Nelson(74) *Attorney, Agent, or Firm* — Holland & Hart, LLP(57) **CLAIM**

The ornamental design for the shoe sole, as shown and described.

DESCRIPTION

FIG. 1 is proximal view of a shoe sole according to the present disclosure.

FIG. 2 is bottom view of the shoe sole of FIG. 1.

FIG. 3 is a lateral view of the shoe sole of FIG. 1 with the unclaimed upper shown in FIG. 1 removed.

FIG. 4 is a medial view of the shoe sole of FIG. 1 with the unclaimed upper shown in FIG. 1 removed.

FIG. 5 is a cross-sectional view of the shoe sole of FIG. 2 along lines 5-5.

FIG. 6 is a cross-sectional view of the shoe sole of FIG. 2 along lines 6-6; and,

FIG. 7 is a cross-sectional view of the shoe sole of FIG. 2 along lines 7-7.

The features shown in broken lines depict unclaimed portions of the shoe sole as well as environmental structure associated with the shoe sole in a condition of use. The broken lines and structure they depict form no part of the claimed design.

1 Claim, 6 Drawing Sheets---
